(57) **CLAIM**

The ornamental design for a handgun holster, as shown and
described.

DESCRIPTION

FIG. 1 is a top rear perspective view of the handgun holster
in accord with our design;
FIG. 2 is a rear elevational view thereof;
FIG. 3 is a front elevational view thereof;
FIG. 4 is a right side elevational view thereof;
FIG. 5 is left side elevational view thereof;
FIG. 6 is a top plan view thereof; and,
FIG. 7 is a bottom plan view thereof.

The broken lines in all the drawings are representations of
the handgun and form no part of the handgun holster of this
invention.
